(57) **CLAIM**

The ornamental design for a desk organization pegboard, as shown and described.

DESCRIPTION

FIG. 1 is a perspective of the desk organization pegboard showing my new design;

FIG. 2 is a perspective thereof from another angle;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof in a state of use.

The broken lines show portions of the desk organization pegboard that form no part of the claimed design.

1 Claim, 9 Drawing Sheets
